(57) **CLAIM**

The ornamental design for a truck cabin as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a truck cabin showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The grayscale shading illustrates contour and contrast in appearance, not surface ornamentation or any particular color.

The bottom view is omitted and forms no part of the claimed design.

The portions of the truck cabin depicted in dot-dash broken lines form no part of the claimed design.
